(57) **CLAIM**

The ornamental design for a ball pit, as shown and described.

DESCRIPTION

FIG. 1 is a perspective view of a ball pit of the present invention, which shows a bottom and a wall of the ball pit are integrated together by a zipper closed.

FIG. 2 is another perspective view of FIG. 1, which shows the bottom and the wall of the ball pit are separated from each other by the zipper opened.

FIG. 3 is a front view of FIG. 1.

FIG. 4 is a back view of FIG. 1.

FIG. 5 is a right side view of FIG. 1.

FIG. 6 is a left side view of FIG. 1;

FIG. 7 is a top plan view of FIG. 1; and,

FIG. 8 is a bottom plan view of FIG.
